Inventor

John G. Robinson

JOHN G. ROBINSON, OF SPRINGFIELD, ILLINOIS.

Letters Patent No. 88,414, dated March 30, 1869; antedated March 22, 1869.

IMPROVEMENT IN TRENCH-PLOW.

The Schedule referred to in these Letters Patent and making part of the same.

Be it known that I, JOHN G. ROBINSON, of Springfield, Sangamon county, State of Illinois, have invented a new and useful Improvement on Trench-Plows; and that the following is a clear, exact, and full description of the construction and operation of the same, reference being had to the accompanying drawing, and to the letters of reference marked thereon.

T represents a stationary steel coulter, with a sharp edge in front, which is attached to the heel of the sod-plow U, extending downward, and sloping backward, and lying against the landside of the trench-plow, for

the purpose of cutting the furrow-slice for the trench-plow V.

What I claim as my invention, and desire to secure by Letters Patent, is—

The attaching this stationary coulter to the heel of the sod-plow, extended downward and sloping backward, for cutting the furrow-slice of the trench-plow, in the manner described.

Witnesses: JOHN G. ROBINSON.
